PROCESS FOR TREATING GRAVEL

William H. Allswede, Hersey, Mich.

Original application August 1, 1930, Serial No.
472,376. Divided and this application April
19, 1934, Serial No. 721,268

5 Claims. (Cl. 209—6)

This invention relates to an improved process for treating gravel to eliminate rotten stone, hard clay and the like. The application is a division of my co-pending application for Patent Ser. No. 5 472,376 filed August 1, 1930.

The objects of the invention are:

First, to eliminate hard clay lumps, rotten stone, agglomerates and the like from gravel.

Second, to provide a continuous process for 10 treating gravel as it is fed to eliminate the objectionable material.

Objects pertaining to details and economies of construction and operation will appear from the description to follow. In the accompanying 15 drawings, which shows an apparatus suitable for carrying out my invention,

Fig. 1 is a detail elevational view partially in section on line 1—1 of Figs. 2, 3 and 4.

Fig. 2 is an enlarged rear end elevation taken 20 from the left hand of Fig. 1.

Fig. 3 is an enlarged detail cross sectional view on line 3—3 of Fig. 1, showing details of the tumbling barrel means.

Fig. 4 is a similar detail cross sectional view 25 on section line 4—4 of Fig. 1, through the gravel rinsing screen part.

Fig. 5 is a detail perspective view of one of the liner sections.

Fig. 6 is a detail sectional view on line 6—6 30 of Fig. 5 showing details of construction.

The parts will be identified by their numerals of reference which are the same in all the views.

1 is a cylindrical drum of the ball mill barrel, 35 preferably 48 to 72 inches in diameter and of cor-

responding length as illustrated. In practice it is supported at an inclination of one and one-half inches to the foot, the higher end being the feed end and the lower end being the discharge end. 2 is a cylindrical gravel rinsing and grading

40 screen of like diameter to the said drum 1, secured to the discharge end thereof for screening the gravel after it has been scrubbed. It contains appropriate screen slots to secure the grade and size of gravel required. 3 are bearing rings which

45 surround the same, two being shown in the structure. These are supported on pairs of rollers 4, the rollers on each side being carried on shafts

41 which are supported in suitable bearings 42, 42 on a base 5. Gear ring 6 is provided at a con-

50 venient point along the length of the drum 1 to drive the same by suitable pinion in a well known manner. The pinion and driving means are not shown, as my invention does not pertain thereto.

The feed end of my improved drum is closed by 55 the plate 7 which has a central circular opening

11 for the intake of material. The interior of the barrel is divided into compartments by plate rings 8, seen particularly in Fig. 1, a plate being shown at the extreme end of said drum. To these plates 8 are secured conical scrubbing screens 9 of about the proportion shown, which conical screens contain round holes one and three-fourths inches in diameter or larger so as to pass the material to be scrubbed, and about one-half inch apart. The gravel introduced is 10 screened for size so that all large pieces are eliminated. The inner ends of the screens 9 are closed by removable caps 91 to facilitate repair and to permit introduction of the steel balls 92. Each compartment of the drum is lined with steel 15 plates 10 which carry inch square longitudinal bars 11 which are riveted thereto, said lining being detachably secured so that it can be readily renewed when worn.

Within the compartment I place a quantity of 20 steel balls 92 of such size that they will not pass through the apertures in the screens 9. These balls in practice are steel about two to four inches in diameter. Of course, cast iron balls or round stones might be used.

In operation the perforated water pipe 13 connected to a supply 14 delivers water to the rinsing and grading screen 2. My improved mill is very

effective if but a single length of scrubber with the rinsing and grading screen is provided. However, its action is greatly enhanced by a

plurality and in practice I have used four ordinarily, as illustrated in the drawings. In the operation, gravel, containing impurities such as

clay and rotten stone and other hard stratified material, is introduced into the drum at 11 by

any suitable means, as by chute or belt conveyor. A quantity of water is introduced at the

same time by hose or otherwise, enough to reduce the mass to a muddy consistency. The ma-

chine is then revolved, all tendency of the ma-

terial to stratify in the drum being obviated by the agitating bars 11 which carry the material

and the steel balls together up at the side and

permit them to tumble down with a crushing

action which quickly disintegrates all clay and

rotten stone or like impurities within the mass

of gravel and does not in any way grind the

gravel. It is not the intent to grind the gravel.

As soon as the machine is started, a continuous

supply of the gravelly material to be treated is

fed into the drum with the necessary water to

secure the muddy consistency and the action, the

same being continuous after the start.

Owing to the incline of the drum this muddy

55

material with the tumbling balls passes up into the conical screen 8 and then, owing to the large size of the perforations therein, the material is at once passed and crushed through to the next compartment where the operation is repeated and is repeated a sufficient number of times to disintegrate the rotten stone or clay.

When this is accomplished the whole mass of the material is discharged onto the gravel rinsing and grading screen 2 where the rinsing takes place. The disintegrated clay and rotten stone is at once washed away and the gravel is passed to a suitable bin or other point of discharge completely prepared for use and all objectionable material removed.

Having thus described my invention, what I claim as new and desire to secure by Letters Patent is:

1. The continuous process of treating gravel to remove objectionable material such as rotten stone, hard clay lumps or the like, comprising moistening the gravel containing such objectionable material until it has a muddy consistency, feeding the gravel continuously, mixing with the gravel disintegrating elements larger than the gravel, agitating the mixed gravel and disintegrating elements until the objectionable material and not the gravel is disintegrated, and while thus agitating the mixture screening out the disintegrating elements and separating the gravel from the disintegrated objectionable material.

2. The continuous process of treating gravel to remove objectionable material such as rotten stone, hard clay lumps or the like, comprising, feeding the gravel continuously, mixing with the gravel disintegrating elements larger than the gravel, agitating the mixed gravel and disintegrating elements until the objectionable material

and not the gravel is disintegrated, and while thus agitating the mixture screening out the disintegrating elements and separating the gravel from the disintegrated objectionable material.

3. The process of treating gravel to remove objectionable material such as rotten stone, hard clay lumps or the like, comprising moistening the gravel containing such objectionable material until it has a muddy consistency, mixing with the gravel disintegrating elements larger than the gravel, agitating the mixed gravel and disintegrating elements until the objectionable material and not the gravel is disintegrated, and while thus agitating the mixture screening out the disintegrating elements and separating the gravel from the disintegrated objectionable material.

4. The process of treating gravel to remove objectionable material such as rotten stone, hard clay lumps or the like, comprising mixing with the gravel disintegrating elements larger than the gravel, agitating the mixed gravel and disintegrating elements until the objectionable material and not the gravel is disintegrated, and while thus agitating the mixture screening out the disintegrating elements and separating the gravel from the disintegrated objectionable material.

5. The process of treating gravel to remove objectionable material such as rotten stone, hard clay lumps or the like, comprising mixing with the gravel disintegrating elements, agitating the mixed gravel and disintegrating elements until the objectionable material and not the gravel is disintegrated, and removing from the gravel the disintegrating elements and separating the gravel from the disintegrated objectionable material.

WILLIAM H. ALLSWEDE.
